UNITED STATES PATENT OFFICE.

WALTER CLIFFORD, OF LONDON, ENGLAND.

CRUTCH.

1,264,774.

Specification of Letters Patent. Patented Apr. 30, 1918.

Application filed November 5, 1917. Serial No. 200,351.

To all whom it may concern:

Be it known that I, WALTER CLIFFORD, a subject of the King of Great Britain and Ireland, residing at London, in the county 5 of Middlesex, England, have invented new and useful Improvements in Crutches, of which the following is a specification.

This invention relates to crutches for cripples, and it has for its object so to construct these appliances as to relieve, or prevent, pressure under the armpits of the user, and so obviate what is known as "crutch paralysis", which is caused by the great strain which comes under the arm-pits and 15 is occasioned by the use of crutches as now constructed.

And in order that my invention may be readily understood, I will now describe it fully with reference to the accompanying 20 drawings, wherein:

Figure 1 is a perspective view of the improved crutch, and

Fig. 2 an underside view of one form of seating contrivance made use of therewith, 25 and drawn to a larger scale than Fig. 1.

For the purpose of my invention there is pivotally suspended, at any suitable points between the crutch staves *a*, say at the lower part of the arm-supports *a*¹, by chains *b* 30 (or by straps and buckles, and pulleys) a seat *c*, or other appropriate supporting device designed to receive the weight of the body of the user, and by means of which he is suspended, thereby relieving him of any 35 pressure under his arm-pits, or on the hand, or hands, and so preventing soreness, as it is possible, with my construction of crutch, to use the same without the hands, as hereinafter explained.

These chains *b*, are attached by hooks *b*¹, at their lower ends, to cross-bars *c*¹, *c*², provided with eyes *c*³, or with hooks, rings, swivels, or studs, said cross-bars being connected together by a bar *c*⁴ extending between them, and between these cross-bars the seat is mounted. The bar *c*⁴ is disposed below the seat or supporting contrivance *c* and has upturned ends which are secured to the upturned ends *c*⁵ which are secured to the central portions of the cross-bars *c*¹ and *c*². The chains *b* are attached, at their upper ends, by means of their links to yokes or levers *d*, pivoted at *d*¹, to the inner faces of the arm-supports *a*¹, and terminating in hooks *d*². Thus, according to which ones

of the links of the chains are hooked on to the hooks *d*² of the yokes *d*, the adjustment of the seat, that is to say the raising, or the lowering, of the same is readily obtained, so adapting the seat to the stature of the 60 user, and by thus relieving him of pressure renders the appliance comfortable for him.

The seat or supporting contrivance *c* has a forwardly projecting bar or arm *c*⁶ connected at its front end to the center of the 65 forward cross-bar *c*¹, and to the rear of this seat or supporting contrivance springs *s* are attached and also connected to the opposite extremities of the rear cross-bar *c*², as clearly shown by Fig. 2. Connected to the bar or 70 arm *c*⁶ by a hook *c*⁶ is an adjusting screw-rod *c*⁷ which extends through the center of the bar *c*¹ and is engaged by an adjusting nut *c*⁸. The seat or supporting contrivance may take the form of an ordinary cycle 75 saddle (as shown in the drawings) and may be made so as to be inflated; or it may be stuffed or padded with an appropriate resilient material; or it may take the form of suitably shaped pads, which may also 80 be constructed as to be inflatable, or to receive padding or stuffing. When in the form of pads, these would pass under the "fork" of the user and would support him between the crutches, thereby obviating any 85 pressure under the arm-pits. Or, again, the suspended supporting device may take the form of a pair of breeches. In every case the supporting device would be suspended substantially in the manner above 90 described between the crutch staves.

The seat, or other weight-relieving and suspended supporting device, being detachable from the chains, or the like, any of the forms of seat device above mentioned may 95 be employed with the same pair of crutches.

Crutches constructed as above set forth may be secured to the body of the user by means of straps adapted to be passed around his chest, or over his shoulders, and arranged to buckle in front, so leaving him the free use of his arms (or arm, should he have lost one) while permitting him to get about easily on his crutches. And in a case where the user has lost an arm or a hand, 100 the crutch corresponding to the lost arm or hand can be secured to the stump of such arm by means of a strap and buckle, or otherwise, so enabling him to get about freely, simply by maintaining the stump 105 110

and crutch staff firmly pressed against his side.

Any, or all, of these supporting devices or contrivances may be so constructed as to prevent pressure on the perineum.

Crutches constructed as above described obviate the necessity of using springs with the arm-supports, and at the bottoms of the staffs.

Having now described my invention, what I claim and desire to secure by Letters Patent, is:

1. The combination, with a pair of crutches, of a pivotally suspended seat, and means for adjusting the said seat, to suit the requirements of the user.

2. In a crutch of the class specified, the combination with crutch members having the usual arm supports, a movably suspended supporting contrivance, a suspending means pivoted at a suitable point to each arm support, and flexible suspending means adjustably and detachably connected to the

suspending means and to the supporting contrivance.

3. In a crutch device of the character specified, the combination of crutch members having the usual arm supports, and means located between and connected to the said members for supporting a part of the human body between said members and materially relieving the arm supports of the body weight.

4. In a crutch device of the class specified, the combination of crutch members, and body-engaging supporting means between the crutch members, said means being adjustably connected to and movably suspended between said crutch members.

In witness whereof, I have hereunto signed my name in the presence of two subscribing witnesses.

WALTER CLIFFORD.
